UNITED STATES PATENT OFFICE.

DAVID A. GABAY, OF NEW YORK, N. Y., ASSIGNOR TO MCKESSON & ROBINS, OF SAME PLACE.

DESIGN FOR A SPONGE-BASKET.

SPECIFICATION forming part of Design No. 13,508, dated January 2, 1883.

Application filed October 20, 1882. Term of patent 7 years.

To all whom it may concern:

Be it known that I, DAVID A. GABAY, of the city, county, and State of New York, have invented and produced a new and original 5 Design for Sponge-Baskets, of which the following is a specification, reference being had to the accompanying drawing, forming part thereof, in which a perspective view of my newly-designed sponge-basket is shown.

10 The sponge-basket A, which can be made of wire-netting, willow-ware, or any other suitable material, is made in the general shape of an obelisk. The peak of the pyramid-top of the obelisk may be surmounted by an acorn, 15 B, or some other suitable knob, button, or ornament. The basket is divided into a series of compartments by horizontal partitions, and in one side of each compartment a semicircular or other opening, C, is formed for passing 20 the sponges in and out of the compartments, which openings also ornament the sides of the

obelisk and enliven the flat surface of the same. The basket may be provided with doors for the said openings, if desired. The basket may be provided with casters.

I do not limit myself to any given size or proportion of the obelisk, but prefer the following dimensions: twenty-two inches square at base and sixty-five inches high, and eighteen inches square at base and fifty-five inches high. 25 30

I claim—

1. The herein - described newly - designed sponge-basket, made in the shape of an obelisk with a pyramidal top, as set forth.
2. The herein - described newly - designed sponge-basket, made in the shape of an obelisk, having a knob on the peak of the top pyramid of the obelisk, as set forth.

DAVID A. GABAY.
